(57) **CLAIM**

The ornamental design for a hanging strap as shown and described.

DESCRIPTION

FIG. 1 is a perspective view of a hanging strap showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view taken along line 8-8 of FIG. 2;

FIG. 9 is a cross-sectional view taken along line 9-9 of FIG. 2;

FIG. 10 is a cross-sectional view taken along line 10-10 of FIG. 2;

FIG. 11 is a cross-sectional view taken along line 11-11 of FIG. 2; and,

FIG. 12 is a perspective view of the hanging strap in a state of use with broken line environment.

The dot-dash broken lines in FIG. 2 are included for the purpose of illustrating the sources of the sectional views and form no part of the claimed design.

The hatching in FIGS. 8 to 11 are for illustrating the cross-sections only, and is not for limiting the material.

The dashed broken lines in FIG. 12 are for illustrating environment structure only and form no part of the claimed design.
